UNITED STATES PATENT OFFICE.

FRANK J. W. WEISER, OF CHICAGO, ILLINOIS, ASSIGNOR TO GEORGE P. BENT COMPANY, OF CHICAGO, ILLINOIS, A CORPORATION OF ILLINOIS.

MUSIC-BENCH.

1,172,415.

Specification of Letters Patent. Patented Feb. 22, 1916.

Application filed March 5, 1915. Serial No. 12,241.

To all whom it may concern:

Be it known that I, FRANK J. W. WEISER, a citizen of the United States, residing at Chicago, in the county of Cook and State of Illinois, have invented certain new and useful Improvements in Music-Benches, of which the following is a specification, reference being had therein to the accompanying drawing.

10 My invention relates to music benches, and its object is to provide a novel organization and arrangement of parts providing a horizontal seat for manual playing purposes, a forwardly inclined seat for player-piano purposes and a music cabinet in which the part forming the seat when the device is used as a player-piano bench, forms the rear cover or closure of the music cabinet when the device is used as a bench for manual playing.

15 In the accompanying drawings which represent a practical embodiment of my invention Figure 1 is a perspective view with the player-piano seat in position for such use; Fig. 2 is a view in rear elevation when the parts are arranged as in Fig. 1 and showing the preferred interior arrangement of the music cabinet; Fig. 3 is a sectional view on the line 3—3 of Fig. 2 with the player-piano seat shown in full lines in its position 20 to close the music cabinet and in dotted lines in its other position; and Fig. 4 is a detail sectional view on the line 4—4 of Fig. 3 showing the pivotal arrangement of the player-piano seat.

25 In the drawings the reference letter A represents four upright corner legs of the piano bench connected together by the usual cross pieces a, B represents the front panel, C the end panels and D the bottom forming an interior music cabinet which preferably is provided with horizontal shelves E for music or music rolls. The top of the cabinet is closed by the horizontal seat F forming the seat for manual playing purposes and 30 fixed in position in a plane below the top edges of the ends which are provided with the usual finishing rails c. The supplemental or piano player seat is provided by the swinging panel G which is hinged at its 35 rear end corners to the rear upper ends of the frame by any suitable hinges which will permit it to assume the two positions shown

in full and dotted lines in Fig. 3, such for example as the pintles H secured on the rear corners of the seat G and entering corresponding holes in the upper ends of the rear legs, the plates composing the hinge preferably being counter sunk in the associated parts as shown in Fig. 4 to strengthen the connection. The seat G is supported in inclined position when used for its seating purpose by any suitable means, such as the stops I secured to or forming a part of the frame at the front corners of the horizontal seat F and arranged so that the front edge 55 of the seat G will be lower than its rear edge to give the desired forward and downward inclination when the bench is used by the player to operate a mechanical piano-player. When the bench is used 60 for manual playing purposes the seat G is turned on its hinges and swung to the position shown in full lines in Fig. 3, the width of the seat G being sufficient to close the rear open end of the cabinet as shown in Fig. 3 65 70 so that it forms a cover therefor and leaves the seat F at regular piano height for manual playing purposes. When the bench is to be used with a player-piano the seat G is swung to the position shown in full lines in Fig. 1 and in dotted lines in Fig. 3, where it provides a forwardly inclined seat at regular height, which is usually above the height 75 of a seat used for manual playing. When the seat G is swung to this position its free 80 edge rests upon the stops I and it leaves the music cabinet open for easy access to the 85 contents thereof.

I claim:

1. A music bench comprising a frame 90 composed of four uprights, front, end and bottom panels forming a music cabinet, a horizontal seat fixed to the frame below the upper edges of the ends and forming a top for the cabinet, a supplemental seat pivoted 95 at its rear edge to the rear upper ends of the frame above the horizontal seat and forming a rear closure for the cabinet when it is swung down in rear thereof, and stops for the front edge of the pivoted seat to hold 100 said seat in inclined position when it is swung into its seating position above the fixed seat.
2. A music bench comprising an upright

frame, a seat-member horizontally supported on the frame below the upper portion thereof, a second seat-member pivotally connected at one edge at the upper portion of the frame above the first seat-member to swing into positions above and at one side in the rear of the first seat-member, and stops to hold said second seat-member in inclined

position when it is swung into place above said first seat-member. 10

In testimony whereof I affix my signature in presence of two witnesses.

FRANK J. W. WEISER.
